GARMENT BLOCKER

Kenneth R. Larson, Des Plaines, and John G. Bilz,
Niles, Ill., assignors to Carl B. Albert, Milwaukee, Wis.

Application February 23, 1946, Serial No. 649,487

16 Claims. (Cl. 223—69)

1

This invention relates to adjustable frames such as garment blockers and more particularly to improved adjustable locking devices therefor, although it and certain features thereof may be employed with equal advantage for other purposes. This application is a continuation-in-part of our copending application Serial Number 649,486, filed February 23, 1946.

It contemplates more especially the provision of improved adjustable frame guide and resilient fastener means for rendering such adjustable and maintaining the elements thereof in any adjusted relation within their intended size range or limit.

Adjustable frames usually embody overlapping wires and this is true of blockers or driers for garments which are normally of varied style and size to conform with the dimensional and shape characteristics of different individuals. In order to effectively block various sized garments of knit construction, it is highly desirable to have the blocker adjustable to different shapes and sizes as well as positional support, thereby requiring the component elements thereof including the sleeves to be readily adjustable and easily maintained in adjusted relation to meet the problems incident to drying, display and fittings.

Most garments vary in contour as well as shoulder and hip characteristics in the same sizes to the end that it is almost impossible to properly block every possible knit garment within the same general size dimensions. In order to overcome shortcomings of ordinary garment blockers as well as to preclude the necessity of stocking numerous types of garment blocking devices, it is proposed to provide adjustment features to conform with specifically shaped and sized garments in order to support, dry, shape or block such in an expeditious manner.

Numerous types of adjustable frames such as garment blockers have heretofore been proposed, but the adjustable retaining means on these have either been too expensive or are not entirely satisfactory from a production and operation standpoint owing to the inability to render such quickly adjustable without entailing any appreciable manipulation, difficulty and production expense. Most locking expedients are either structurally intricate or expensive in production or will not satisfactorily operate unless produced and assembled within precision tolerances or for that matter involve moving parts which do not always function satisfactorily for use with garments of greatly varying size. Further, considerable difficulty is encountered in maintaining the component elements thereof in

adjusted relation without the adjusting or locking means serving as an obstruction to the garment.

It must be appreciated that in the use of garment blockers, such necessarily are subjected to the wet garments so that the component elements thereof must be readily associable and removable relative to the garment without obstruction thereto or causing undesirable stretch thereof. It is also desirable that the component elements and the expedients for maintaining such in adjusted relation should not become involved with the material of which the garment is made nor should such protrude to any extent to avoid impairment to the garment. This is particularly true of the sleeves which usually are attached to frame eyelets that interrupt smoothness of garment contour and obstruct the garment in the association thereof with the frame, especially when the arm forms are not utilized which occurs often within the judgment of the user and the requirements of the garment.

With the teachings of the present invention, the adjustable retaining means are shaped from the frame wire to comprise an integral portion thereof. The arm forms have their own integral retainers for frictional adjustable grasp of the smooth frame wire to render such readily attachable and detachable relative to the frame body, easily adjustable in size, and inexpensive in construction.

One object of the present invention is to provide improved adjustable locking means for blockers to conform with various sized and styled garments.

Another object is to provide improved, more simple and less expensive adjusting expedients for garment blockers having shoulder and/or waist and/or skirt portions readily adjustable to meet different styled and sized garment characteristics.

Still another object is to provide improved and less expensive frame guiding and locking expedients integrally shaped from frame portions to afford effective blocker adjustments to accommodate varied garments for expeditious garment blocking.

A further object is to provide novel wire guiding and locking means integral with garment blocker frames for maintaining such in adjusted size without the locking means serving as an appreciable obstruction to the garment.

A still further object is to provide improved, dependable, and simple combination overlapping frame wire guiding and locking means shaped

2

from the frame body for maintaining garment blockers and their appendages in adjusted position to effectively stretch and maintain selected adjustable sizes in clothes during the drying thereof.

Still another object is to provide an improved adjustable frame and arm guiding and locking means that do not embody movable parts for maintaining garment blockers in adjustment and afford instant adjustment and convenient manipulation responsive to a relative displacing urge on the frame elements.

Other objects and advantages will appear from the following description of an illustrative embodiment of the present invention.

In the drawings:

Figure 1 is a top plan view of a garment blocker having improved adjusting fasteners embodying features of the present invention.

Figure 2 is a front view in elevation of the garment blocker shown in Figure 1 with the sleeve appendages associated therewith.

Figure 3 is an enlarged fragmentary front view in elevation of an upper frame spring guiding bracket and hook shown in Figures 1 and 2 assembled with the garment frame.

Figure 4 is an enlarged fragmentary sectional view of the frame overlapping portions taken substantially along line IV-IV of Figures 1 and 2 showing the spring guiding bracket and hook.

Figure 5 is an enlarged fragmentary top sectional plan view of the spring guiding bracket taken substantially along line V-V of Figure 3.

Figure 6 is a detail enlarged front view in elevation of extensible bottom frame overlapping portions provided with guiding and retaining elements of the type shown in Figure 2.

Figure 7 is a detail enlarged front view in elevation of extensible bottom frame overlapping portions provided with modified guiding and retaining elements.

Figure 8 is a detail enlarged front view in elevation of extensible bottom frame overlapping portions provided with still further modified guiding and retaining elements.

The structure selected for illustration is not intended to serve as a limitation upon the scope or teachings of the invention, but is merely illustrative thereof. There may be considerable variations and adaptations of all or part of the teachings depending upon the dictates of commercial practice. The present embodiment comprises any suitable adjustable frame 10 consisting of a plurality of sections such as 11 and 12, in this instance two, preferably though not essentially bent or otherwise shaped from wire to provide overlapping upper portions 13-14 and overlapping lower portions 15-16, although intermediate overlapping wire elements may be provided should commercial practice so dictate. The frame sections 11-12 define, in this instance, an adjustable sweater garment blocker, although the particular configuration thereof may be varied within a wide range depending upon the dictates of commercial practice.

So that the frame sections 11-12 may be adjustable in size responsive to guiding and displacing the overlapping wire frame portions 13-14 and 15-16 relative to each other and to confine them slidably to extensible adjacent relation, each of the upper overlapping wire frame portions 13-14 and the lower overlapping wire frame portions 15-16 have, in this instance, combined guiding and frictional retaining fasteners associated with each or preferably bent or ar-

ticulated therefrom for yielding contact with the adjacent overlapping portions to maintain them in any desired extensible relation. To this end, the combined guiding and retaining elements for the lower superposed overlapping wire frame portions 15-16 preferably comprise integral spring clips 17-18 bent or otherwise shaped from the extremities of the overlapping wire frame portions 15-16, respectively.

The spring clips 17-18 (Figures 2 and 6) are identical in shape, structure and functional characteristics to those illustrated and described in our above identified copending application, and any further description thereof would be merely repetitious in that these are inverted and oppositely disposed to serve the same function on their respective bottom frame overlapping wire portions 15-16. This is also true of the sleeve forms 19-20 which have spaced diagonally connected convolutions defining spring clips or clamps 21-22 and 23-24 on the upper and lower extremities of the sleeve forms 19-20, respectively. The sleeve form clips 21-22 and 23-24 are fully illustrated and described in the above designated copending application and require no further explanation herein. The sleeve forms 19-20 or their counterparts, the modified short sleeve forms 19'-20' are readily attachable and detachable to the garment frame sections 11-12 in the arm pit regions 25 and 26 thereof as well as adjustable therealong as shown in dotted outline in Figure 2.

As shown, the overlapping frame portions 13-14 terminate in any suitable finger grasping extremity such as the eyelets 27-28, respectively, turned or otherwise provided thereon to enable the relative sliding thereof in parallel spaced relation by simultaneous manual forces thereon to effect their approach or recession in sizing the frame 10 for the major area thereof save the bottom overlapping portions 15-16 that have their own individual adjusting expedients 17-18, respectively. By causing the recession of the finger grasping ends 27-28 of the overlapping portions 13-14, the garment frame 10 is narrowed considerably in size to assume any shape such as is shown in dotted outline in Figure 2. This reduction in size of the frame 10 enables slip-over sweaters to be introduced thereon by inserting the neck through the bottom overlapping portions 15-16 when reduced to its narrowest size and, thereupon, one shoulder is then provided on the rounded arm pit portion 25 and the other on the opposite arm pit portion 26 so that one shoulder is on the overlapping wire 13 and the other on the overlapping wire 14 which are in horizontal alignment in spaced relation to permit one and then the other of the garment shoulders thereon. For that matter, a cardigan sweater as well as a slip-over type may be shaped and dried on a frame structure 10, and this is rendered possible by the narrow bottom configuration 15-16 thereof to permit the neck of the sweater to be inserted thereover without imparting any undesirable stretch therein.

In order to maintain the top overlapping portions 13-14 in spaced relation and to retain them in their desired adjusted relative slidable relation, an improved retainer is provided which, in this instance, takes the form of a hook 29 bent from wire upon itself to present a solid hook end 30 and extending downwardly in a series of twists 31 to provide diverging shanks 32-33. The diverging shanks 32-33 terminate in spaced planes forwardly and backwardly for a distance

to provide the desired spacing of the top frame overlapping portions 13-14. To this end, each of the shanks 32-33 merge into counterclockwise and clockwise wound diagonally opposite convolutions 34-35, respectively (viewed from Figure 4), at the spaced ends of the diverging shanks 32-33 to receive the frame overlapping wires 13-14 therethrough along with other convolutions as will appear more fully hereinafter (Figure 5).

Each of the diagonally opposite convolutions 34-35 is contiguous with an oppositely wound convolution 36-37, respectively, that are also diagonally opposite to receive the other of the two frame overlapping wires 13-14 in spaced aligned relation with the initial convolutions 34-35, respectively. Each of the diagonally opposite convolutions 36-37 is contiguous with a linear series of adjacent convolutions 38-39, in this instance eleven, which define substantially straight cylindrical tubular members in alignment with the original diagonally opposite shank merging convolutions 34-35 to support the top frame overlapping wires 13-14 therethrough in parallel spaced relation to each other. It should be noted that the end convolution 40-41 of each of the convolution series 38-39 terminate in the space between the initial convolutions 34-35 and the next adjacent space provided to accommodate the hook extremity shank 32-33 to substantially meet therewith and thus present smooth enclosed end convolutions 34-36 and 35-37 which avoid any sharp obstruction which would snag or otherwise impair the garment disposed over the frame 10.

It should be noted that the terminal ends of the top frame overlapping members 13-14 are provided thereon after the wires 13-14 have been projected through the linear series of cylindrical tubular member forming convolutions 38-39 which present a surface frictional reaction with the somewhat smaller top frame overlapping members 13-14 that are curved or arcuate compared to the straight cylindrical tubular member convolutions 38-39 and, therefore, present frictional reacting surfaces therewith. While parallel spaced tubular members may be utilized in conjunction with arcuate frame overlapping wire portions 13-14 to present frictional telescopic association therewith, yet the cylindrical tubular series of convolutions 38 are more advantageous in that they yield sufficiently in a transverse direction to partially conform with the curvature of the frame overlapping wires 13-14 to present sufficient friction to retain them in their relative adjusted relation and still provide for their relative displacement without impairment to the finish or surface of the wire frame overlapping members or portions 13-14.

This construction presents an effective hanging hook 29 for the entire frame 10 and simultaneously serves to maintain the top frame overlapping members 13-14 in parallel spaced adjusted relation for the convenience and effective manual variation of the size and contour of the frame 10 to conform with a garment of the desired resultant size after drying thereon. It should be noted that with a frame 10 of the described and illustrated structure, it would be desirable to provide such in a number of different size ranges such as small, medium, and large to accommodate infant, junior and adult garments, respectively, from the smallest to the largest for both the male and female styles. The terminal enlarged ends 27-28 of the members 13-14 pre-

clude the removal of the hook 29 and its spaced parallel series of convolutions 38-39 from the frame 10.

In the modified embodiment shown in Figure 5, the bottom overlapping frame portions 15'-16' of the frame sections 11'-12' comprising the frame 10', terminate in oppositely extending and laterally offset series of convolutions 17'-18' which offer the desired frictional reaction with the wires 16'-15' to maintain them in their desired relative displacement for determining the size of the lower frame region 10'. This arrangement of convolutions 17'-18' on the terminal ends of the overlapping bottom frame members 15'-16' would have to be sized to offer enough frictional reaction to permit the relative displacement of the bottom frame overlapping portions 15'-16' and yet effect their retention to their adjusted relative positions. A still further modified embodiment of the bottom frame overlapping portions 15"-16" of the frame section 11"-12" consists in providing end convolutions 17"-18" which are laterally offset to receive the bottom overlapping frame portions 15"-16" in slidable spaced relation and provide sufficient freedom of relative displacement to render it necessary to provide an additional friction expedient such as depending U-shaped fingers 42-43 which have their terminal legs 44-45, respectively, terminate upwardly for surface contact with a series of horizontally spaced vertical notches 46-47 knurled or otherwise provided in the confronting surfaces of the bottom frame overlapping portions 15"-16".

The fingers 42-43 serve the dual function of providing finger grasping manipulating members and also serve as frictional retainers to maintain the bottom portions of the frame sections 11"-12" in their adjusted position. A slight twist exerted on the fingers 42-43 will lessen the frictional reaction thereof with the notches 46-47 on the bottom frame overlapping portions 15"-16" and thus permit comparatively free sliding relative displacement therebetween.

While we have illustrated and described a preferred embodiment of this invention, it must be understood that the invention is capable of considerable variation and modification without departing from the spirit of the invention. We, therefore, do not wish to be limited to the precise details of construction set forth, but desire to avail ourselves of such variations and modifications as come within the scope of the appended claims.

We claim:

1. In a device of the character described, the combination with a garment form having relatively slidable overlapping curved portions for defining adjustable interior shapes of garments to be sized thereon, and straight elongated tubular means frictionally associated with said garment form overlapping curved portions to slidably and resiliently retain said garment form overlapping portions in adjusted overlapping extensible relation relative to said tubular means to support variously sized and shaped garments on said form.
2. In a device of the character described, the combination with a garment form having relatively slidable overlapping portions for defining adjustable interior shapes of garments to be sized thereon, and elongated tubular means frictionally associated with each of said garment form overlapping portions being separated from

the other to slidably guide and resiliently retain said garment form overlapping portions in adjusted overlapping extensible relation to support variously sized and shaped garments on said form.

3. In a device of the character described, the combination with a garment form having relatively slidable overlapping portions for defining adjustable interior shapes of garments to be sized thereon, and elongated tubular convoluted means frictionally associated with each of said garment form overlapping portions being separated from the other to slidably guide and resiliently retain said garment form overlapping portions in adjusted overlapping extensible relation to support variously sized and shaped garments on said form.

4. In a device of the character described, the combination with a garment form having relatively slidable overlapping portions for defining adjustable interior shapes of garments to be sized thereon, and parallel spaced elongated tubular means frictionally associated with each of said garment form overlapping portions being separated from the other to slidably guide and resiliently retain said garment form overlapping portions in adjusted overlapping extensible relation to support variously sized and shaped garments on said form.

5. In a device of the character described, the combination with a garment form having relatively slidable overlapping portions for defining adjustable interior shapes of garments to be sized thereon, and parallel spaced elongated tubular convoluted means frictionally associated with each of said garment form overlapping portions being separated from the other to slidably guide and resiliently retain said garment form overlapping portions in adjusted overlapping extensible relation to support variously sized and shaped garments on said form.

6. In a device of the character described, the combination with a garment form having relatively slidable overlapping portions for defining adjustable interior shapes of garments to be sized thereon, elongated tubular means frictionally associated with said garment form overlapping portions to slidably guide and resiliently retain said garment form overlapping portions in adjusted overlapping extensible relation to support variously sized and shaped garments on said form, and a hook extending from said elongated tubular means to support said garment form.

7. In a device of the character described, the combination with a garment form having relatively slidable overlapping portions for defining adjustable interior shapes of garments to be sized thereon, parallel spaced elongated tubular means frictionally associated with each of said garment form overlapping portions being separated from the other to slidably guide and resiliently retain said garment form overlapping portions in adjusted overlapping extensible relation to support variously sized and shaped garments on said form, and a hook extending from said parallel spaced elongated tubular means to support said garment form.

8. In a device of the character described, the combination with a garment form having relatively slidable overlapping portions for defining adjustable interior shapes of garments to be sized thereon, parallel spaced elongated tubular convoluted means associated with each of said garment form overlapping portions being separated

from the other to slidably guide and resiliently retain said garment form overlapping portions in adjusted overlapping extensible relation to support variously sized and shaped garments on said form, and a hook having rigid converging shanks integrally extending from said parallel spaced elongated tubular convoluted means to support said garment form.

9. In a device of the character described, the combination with a garment frame comprising relatively slidable overlapping sections, said sections having upper overlapping end portions, said upper overlapping end portions having an arcuate complementary curvature, and comparatively straight elongated tubular members for frictionally and slidably receiving each of said upper overlapping end portions therethrough to maintain said overlapping end section portions in relatively adjusted relation to control the size of said garment frame.

10. In a device of the character described, the combination with a garment frame comprising relatively slidable overlapping sections, said sections having upper overlapping end portions, said upper overlapping end portions having an arcuate complementary curvature, and comparatively straight elongated tubular convoluted wire members for frictionally and slidably receiving each of said upper overlapping end portions therethrough to maintain said overlapping end section portions in relatively adjusted relation to control the size of said garment frame.

11. In a device of the character described, the combination with a garment frame comprising relatively slidable overlapping sections, said sections having upper overlapping end portions, said upper overlapping end portions having an arcuate complementary curvature, comparatively straight parallel spaced elongated tubular convoluted wire members for frictionally receiving each of said upper overlapping end portions therethrough to maintain said overlapping end section portions in relatively adjusted relation to control the size of said garment frame, and a hook with converging shanks extending from said convoluted wire tubular members to maintain them in parallel spaced relation.

12. In a device of the character described, the combination with a garment frame comprising relatively slidable overlapping sections, said sections having upper and lower overlapping end portions, said upper overlapping end portions having an arcuate complementary curvature, comparatively straight elongated tubular convoluted wire members for frictionally receiving each of said upper overlapping end portions therethrough, and longitudinally spaced tubular members for frictionally receiving the lower overlapping end portions, said upper and lower overlapping end portions being relatively extensible within said tubular members to maintain said overlapping end section portions in relatively adjusted relation to control the size of said garment frame.

13. In a device of the character described, the combination with a garment frame comprising relatively slidable overlapping sections, said sections having upper and lower overlapping end portions, said upper overlapping end portions having an arcuate complementary curvature, comparatively straight elongated tubular convoluted wire members for frictionally receiving each of said upper overlapping end portions therethrough, longitudinally spaced tubular members for freely receiving the lower overlapping end

portions, and terminal extensions on said longitudinally spaced tubular members to confront the adjacent overlapping section end portions for frictional contact therewith, said upper and lower overlapping end portions being relatively extensible within said tubular members to maintain said overlapping end section portions in relatively adjusted relation to control the size of said garment frame.

14. A supporting bracket for a garment frame 10 having overlapping relatively extensible portions for varying the size thereof, said supporting bracket comprising a hook having diverging shanks, and wire convolutions extending from said hook shanks to define elongated parallel tubular members for frictionally and slidably receiving each of said overlapping extensible frame portions therethrough.

15. A supporting bracket for a garment frame having overlapping relative extensible portions 20 for varying the size thereof, said supporting bracket comprising a hook having diverging shanks, wire convolutions extending from said hook shanks to define elongated parallel tubular members for frictionally receiving each of 25 said overlapping extensible frame portions therethrough, and terminal ends on said wire convolutions interposed between several convolutions of said tubular members for confining the convolution.

16. A supporting bracket for a garment frame having overlapping relatively extensible portions for varying the size thereof, said supporting bracket comprising a hook bent from wire to 35 present diverging shanks, said shanks extending

at their diverging ends into spaced connected convolutions, and wire convolutions extending from one of each of said spaced connected convolutions for alignment with the other of said spaced, connected convolutions on each of said diverging hook shank to define elongated parallel tubular members for frictionally receiving each of said overlapping extensible frame portions therethrough.
